UNITED STATES PATENT OFFICE.

GEORGE T. PHILLIPS AND DAVID F. STAYMAN, OF BALTIMORE, MARYLAND.

DESIGN FOR A DESSERT-FORK.

SPECIFICATION forming part of Design No. 31,575, dated October 3, 1890.

Application filed August 25, 1890. Serial No. 728,509. Term of patent 14 years.

To all whom it may concern:

Be it known that we, GEORGE T. PHILLIPS and DAVID F. STAYMAN, citizens of the United States, residing at Baltimore, in the State of Maryland, have invented and produced a new and useful Design for a Dessert-Fork, of which the following is a specification.

This invention relates to a certain new and useful design for dessert-forks, which will be more fully hereinafter explained.

In the accompanying facsimiles or drawings, Figure 1 is a perspective view of a fork embodying the design. Fig. 2 is a top plan view of the same. Fig. 3 is a transverse vertical section on the line $x-x$ of Fig. 2.

Similar numerals of reference are employed to indicate corresponding parts in the several views.

The numeral 1 designates a handle having a head 2, from which projects a series of tines 3. The tines 3 are substantially straight and have between them divergent spaces having their reduced portions terminating at the head 2, and thus provide the tines with opposite inclined or converging edges.

The particular feature of the design is the

configuration of the marginal-tine fork 4, having its inner edge 5 straight and divergent relatively to the adjacent edge of the tine 3 in proximity thereto. From the inner edge 5 of this marginal tine the upper and lower surfaces 6 and 7, respectively, slope downwardly and upwardly to an outer edge 8, thus producing a tine having a wedge shape in cross-section. The edge 8 has a regular elongated curved contour and merges at its rear extremity into the adjacent curved side edge of the head 2. At its front extremity said edge 8 is given a short or abrupt curve 9 to the front terminal of the edge 5.

Having thus described the invention, what is claimed is—

The design for a dessert-fork, as herein shown and described.

In testimony that we claim the foregoing as our own we have hereto affixed our signatures in the presence of two witnesses.

GEORGE T. PHILLIPS.
DAVID F. STAYMAN.
